UNITED STATES PATENT OFFICE

ALEXANDER SELTZER, OF PHILADELPHIA, PENNSYLVANIA

FACE-PLATE FOR FLUSH RECEPTACLES AND THE LIKE AND ITS MANUFACTURE

Application filed April 26, 1930. Serial No. 447,464.

My invention relates to face-plates useful for various purposes, and particularly for covers of electric wiring receptacles such as "flush" receptacles, and for hand plates on swing doors, etc. I aim to provide a composite plate, comprising a sheet of pyralin, or the like, which will afford a serviceable and pleasing outer surface, over a strong, rugged backing, that may be of a material 5 much cheaper than pyralin. Various advantages that can be realized through the invention will appear from my description hereinafter of selected and preferred embodiments.

15 In the drawings:

Fig. I is a perspective front view of a cover-plate conveniently embodying the invention, a portion being broken out to show the construction.

20 Fig. II is a perspective rear view of a backing for such a plate.

Fig. III is a plan view of a pyralin sheet cut to suitable size and shape to serve as a blank for the facing of the device shown in 25 Fig. I.

Fig. IV is a perspective rear view of the same pyralin sheet suitably embossed or formed for application to the backing shown in Fig. II.

30 Fig. V shows a vertical longitudinal section through the backing and facing of Figs. II and IV assembled together, and also the dies that may be used to secure them together.

35 Fig. VI is a rear perspective view of the backing and facing of Figs. II and IV, after they have been assembled and secured together as shown in Fig. V.

As a facing for my composite face plate, I 40 may use a sheet of pyralin (sometimes termed "celluloid"), or any similar material affording a suitable outer surface and adapted to be formed and applied with the aid of heat, as hereinafter described. Sheet pyralin, .020 in. thick is suitable. This may either be a

plain sheet of .020 in. thickness, or a laminated sheet consisting of a plain base .010 in. thick and a "pearl" front .010 in. thick, securely cemented together.

The backing for my composite face plate 50 may preferably be of sheet metal, soft sheet steel .024 in. thick being suitable. Preferably, this may have a "flash" or coating of copper, both for protection against rust and to improve its appearance.

Fig. I of the drawings shows a "toggle" switch plate 10 constructed in accordance with my invention. As here shown, the switch plate 10 is of generally rectangular form, with its edges reduced at 11 on a bevel, and with the usual rectangular opening 12 for the switch arm and the usual countersunk screw holes 13, 13. As here shown, the beveled corners 14 of the switch plate are rounded. The rounding of the corners 14 obviates cracking of the pyralin, which is almost unavoidable on sharp, angular corners, and gives a pleasing appearance in harmony with the soft effects of pearl pyralin. As shown where the switch plate 10 appears in 60 section, the pyralin facing 15 not only has its margin beveled at 11 in conformity to the bevel of the backing 16, but also has its outer portion or edge 17 turned inward around and behind the edge 18 of the backing, so as 65 to hold the facing securely to the backing. In this way, the facing 15 may be kept so taut that no cementing or local attachment is necessary to hold it snug against the backing 16.

Fig. II is a perspective rear view of the sheet metal backing 16, with its margin "turned up" or deflected rearward on about a 40° bevel. The backing 16 may be cut out of sheet metal and embossed to the form shown in Fig. II by a die stamping operation, or in any other suitable way.

Fig. III shows a plain, flat pyralin sheet 15a of suitable dimensions and outline to serve as an initial blank for the facing 15.

As will be seen from the dot-and-dash outline 10a of the completed switch plate, the allowance of material at the rounded corners 14a of the blank 15a is less than along the straight sides, and the material is trimmed away diagonally at 19 adjacent the corners, so that there shall not be an excessive amount to pucker inside the corners after the pyralin is applied to the base.

Instead of shaping the margins of the flat blank 15a of Fig. III to the deflected margins of the backing 16 of Fig. II and turning them inward around the edges 18 of the latter at one single operation, I prefer to first emboss the blank as shown (15b) in Fig. IV, before assembling it with the backing 16. This preforming of the blank 15a may be done by a die-stamping operation, with just sufficient heat to soften the pyralin and give it the necessary pliancy. For this purpose, metal dies may be used, the outer lower die shaped to conform to the front face of the plate 10 as shown in Fig. I, and the inner upper die shaped like the front face of the backing 16 in Fig. II. These dies may be heated by any suitable means (such as electrical heating elements embedded in them) to a temperature of about 125° F. The pyralin need only be held in the dies a very short time,—from two to five seconds, according to the character of the pearl. The best temperature and time for each particular lot of pyralin may easily be determined by trial: too high or too prolonged heating tends to produce a warped, crinkled, and even crumbly product, while too little heating fails to shape the pyralin properly.

As shown in Figs. IV and V, the outer edge portions 17b of the margins 15b of the embossed pyralin blank 15b not only project rearward (and outward) beyond the edges of the backing 16 when the latter is placed in the blank 15b, but are turned rearward to a somewhat greater angle,—exceeding 45° relative to the face, along lines corresponding with the edges 18 of the backing. This facilitates turning the outer portions 17b inward and rearward around the edges 18, as will be seen hereinafter.

A pyralin blank 15b of the form shown in Fig. IV having been produced as above described, or in any suitable manner, the metal backing 16 is placed in it, and the outer portions 17b of the pyralin are turned inward around and behind the edges 18 of the backing. This may be done by a hot die-pressing operation, as shown in Fig. V. For this purpose, the still warm pyralin blank 15b may be placed in a lower die 25 that conforms to the front of the finish plate 10, so as to support the blank 15b over the projected area of the backing 16. The metal backing 16, which has meantime been heated on a hot plate to about 212° F., is then placed in the blank 15b.

As shown in Fig. V, there is a box-like upper

die 26 having in its lower edge a forming channel or groove 27 rounded to an appropriate profile or cross-sectional curvature for turning the projecting portion 17b of the pyralin blank 15b inward as the die 26 descends. This die 26 carries a plate or pad 28, mounted therein on a plurality of helical compression springs 29. The lower outer portion of the upper die 26 (in which is the channel 27) may be heated to about 212° F., by means of an electrical heating element extending all the way around the die. As the die 26 descends, the pad 28 comes down inside the deflected margin of the backing 16, and presses and holds the backing firmly in the pyralin blank 15b,—the pressure increasing as the springs 29 are more and more compressed. As the die 26 continues to descend, the inward-curving outer side of its channel 27 encounters the portion 17b of the pyralin and progressively deflects and turns it inward and rearward around the edge 18 of the backing 16,—the final result being as shown in section in Fig. I, and in perspective in Fig. VI, which is a rear view of the plate 10 at this stage.

The metal backing 16 and the pyralin facing 15 are both expanded by the heat to which they are subjected in the dies 25, 26, and the pyralin (plastic under the heat) is pressed and shaped into closest conformity to the backing. When they cool off after removal from these dies 25, 26, they both naturally contract or shrink. However, the pyralin facing 15 shrinks more than the metal backing 16, so that it is stretched and held taut against the backing, owing to the firm hold of the hooked portions 17 on the backing. Hence there is no necessity for cementing or otherwise locally securing the pyralin to the backing.

The only remaining step is to form in the plate 10 any openings required for its intended use. This may be done by any suitable punching mechanism, acting on the plate 10 from its front side. Preferably, the punching mechanism will be provided with means for holding the plate 10 firmly, as shown in Fig. V, during the action of the punch or punches. In general, the punching may be done cold; but for large countersunk or bevel-edged openings (as in push-button switch plates), the plate 10 is preferably heated to about 212° F. on a hot plate, just before being put in the punch-press.

My face plate constructed as above described affords many advantages.

Besides presenting a pleasing appearance, it is durable, sanitary, incorrodible, unaffected by atmospheric conditions, does not gather dirt, is easily cleaned, and retains its original lustre and finish indefinitely. It is strong and intransigent, and will not chip or crack; yet it yields to fit any ordinary irregularity of wall surface. Its surface is non-conduc-

tive. Moreover, it can be faced with pyralin of any color desired, and in soft, shimmering pearl effects, as well as in plain colors, so as to harmonize with any scheme of interior 5 decoration.

Having thus described my invention, I claim:

1. A face plate of the character described comprising a sheet metal backing with margins bevelled rearward, and a pyralin facing sheet over said backing having its original integral margins bevelled rearward on those of the backing and turned inward around and behind them.
- 15 2. A face plate according to claim 1, of substantially rectangular outline but having its corners rounded sharply so as to obviate cracking of the pyralin on them without detracting from the generally rectangular effect.

- 20 3. A face plate of the character described comprising a sheet metal backing with margins deflected rearward, and a pyralin facing sheet over said backing, said facing sheet 25 having its original integral margins turned around and behind the margins of the backing, and being shrunk on the backing and thus tautly stretched over the same.

- 30 4. A face plate according to claim 3, of substantially rectangular outline but having the deflected corners of its backing rounded, so as to obviate cracking of the pyralin by stretching on them.

- 35 5. A method of fabricating a face plate comprising a pyralin facing sheet over a sheet metal backing having its margins deflected rearward, which method comprises hot die-pressing a pyralin sheet and thereby deflecting its margins to conform to those of 40 said backing, with their outer portions projecting rearward beyond the edges of said backing, and then hot-pressing and turning said projecting portions around and behind the margins of said backing, so as to lock 45 the pyralin securely to the backing and stretch it taut over the latter when the parts cool.

- 50 6. A method according to claim 5, further characterized in that in performing the margins of the pyralin to conform to the backing, their projecting outer portions are preliminarily bent rearward somewhat in correspondence with the edges of the backing, so as to facilitate turning them around and behind the edges of the backing.

- 55 7. A method of securing over a sheet metal backing with rearward-deflected margins a sheet pyralin facing having its margins deflected rearward conformably to those of said 60 backing, with their outer portions projecting rearward beyond the edges of said backing at an angle to the face of the sheet exceeding 45 degrees; which method comprises holding said backing firmly pressed into said 65 facing while supporting the latter over the

projected area of the backing, and pressing a die-channel of curved profile against the edge of said facing, so as to progressively deflect and bend the projecting portion of the facing margin inward around and behind the 70 margin of the backing, and also heating and thereby softening the pyralin where it is bent.

In testimony whereof, I have hereunto signed my name at Philadelphia, Pennsylvania, this 24th day of April, 1930.
